BINDING POST

William H. B. Lavarack, Pine Bush, N. Y., assignor to Railroad Accessories Corporation, New York, N. Y., a corporation of New York

Application March 23, 1931. Serial No. 524,546

2 Claims. (Cl. 173—259)

This invention relates to electrical apparatus, more especially to conductor connectors, and particularly to those connectors known as binding posts.

5 Those familiar with the electrical arts, and particularly the art of railway signalling, are aware that many cases present themselves in which a large number of binding posts, to which wires are to be attached, are positioned closely adjacent, in fact, so closely together that particular care must be taken that no part of the bare wire or conductor attached to a particular binding post comes in contact with any other binding post.

10 15 This difficulty arising from closely spaced binding posts is rendered worse by the use of flexible stranded conductors. Unless extreme care is taken, one or more of the very thin strands composing the conductor, connected to a particular binding post, are likely to spread and come in contact with an adjacent binding post. An attempt has been made to meet these difficulties with stranded flexible wire conductors by affixing what is technically known as an "eyelet" to the bare end of the wire. This eyelet serves to meet the difficulty in some cases, but the increased size of the conductors has rendered the eyelet solution of the difficulty abortive, because due to the increased size of the stranded conductors and 20 25 30 35 the necessity of keeping the eyelets below a safe maximum diameter, it is quite impossible to prevent some of the strands of the conductor from squeezing out beyond the periphery of the eyelet while the eyelet is being attached to the end of the conductor.

In order to provide a remedy for the difficulties hereinabove enumerated, applicant has devised the present invention.

A principal object of this invention is the production of a binding post of such construction that a plurality of such binding posts may be positioned closely adjacent each other at extremely small distances on centers even when a comparatively large stranded conductor is attached to the binding post, without any substantial danger of loose strands from a conductor connected to one binding post spreading out and coming in contact with an adjacent binding post.

40 45 50 Other objects and advantages will appear as the description of the particular physical embodiment selected to illustrate the invention progresses and the novel features will be particularly pointed out in the appended claims.

55 In describing the invention in detail and the

particular physical embodiment selected to illustrate the invention, reference will be had to the accompanying drawing and the several views thereon in which like characters of reference designate like parts throughout the several views, 60 and in which:

Figure 1 is a front elevational view of a terminal block with two of my improved binding posts in place thereon; Fig. 2 is an elevational end view of the device as shown by Fig. 1; Fig. 3 65 is a top plan view of the device as shown by Fig. 1, but with some of the parts of one of the binding posts removed to more clearly show the construction; Fig. 4 is a cross-sectional view on the plane indicated by the line IV—IV of Fig. 1, 70 viewed in the direction of the arrows at the ends of the line; Fig. 5 is an exploded view of the characteristic parts of applicant's new binding post.

In order to illustrate my improved binding post, 75 I have shown it as applied to what is known as a terminal block. This terminal block consists, in general, of a base 1, of insulating material adapted to be fastened to a support as by a screw passed through orifice 2. The member 1 bears 80 two binding posts designated, generally, A and B. Each binding post has a wire or conductor, shown as stranded, as 3 and 4 respectively, connected thereto.

Each binding post includes the well known bolt 85 5 having a head 6 fitting into a recess 7 of the base so as to prevent turning. A washer 8 and a nut 9 serve to attach the bolt 5 firmly to the base 1. A connector of conducting material, as in the form of an orificed strip 10 electrically 90 connects post A with post B. All of the parts so far described are old and well known in the arrangement as shown and described.

The distinctive and characteristic part of applicant's invention resides in the means co-operating with the bolt 5, and directly with the wire 3. In order to properly connect the large size stranded flexible wire 3 to the bolt 5, applicant first places the member 11 upon the bolt 5. The member 11 may be called an annular 100 trough. This member 11 comprises a sleeve 12, best shown in Fig. 5, surrounded by an annulus 13 connected to the sleeve 12 by the bottom wall 14. The annulus 13 has a wire receiving opening or cut-away portion 15 having rounded edges 105 forming an opening for the passage into the annulus of the conductor 3.

The member 11 is placed on the bolt, generally against an abutment, as 9, thereon, the stranded conductor 3 of large diameter is then 110

bared of its insulation on the end and formed into an approximate annulus or wire coil as shown in Fig. 3, and this wire annulus laid in the annulus 13 resting on the bottom 14 thereof.

5 In order to retain the wire 3 in the annulus 13, and cause a proper pressure to be exerted thereon to form a proper electrical contact, the deep, apertured disc 16 just fitting within the trough and specifically within the annulus 13, and 10 around the sleeve 12 is passed over the bolt 5, and pushed down against the annulus or coil of wire.

In order to maintain deep apertured disc 16 in place, a nut 17 is used, engaging with the threads 15 18 of the bolt 5, and preferably, a washer 19 is interposed therebetween.

The binding post provided by applicant's invention is such that an extremely large diameter stranded wire conductor as 3 may be used and 20 connected securely to a binding post as A without any danger, whatsoever, that any loose strands can be squeezed out sideways so as to come in contact with another binding post closely adjacent thereto, such as one to the right of 25 binding post A, as shown in Fig. 2.

Although applicant has described the principle and operation of his invention and one particular physical embodiment thereof, nevertheless, it is desired to have it understood that the particular 30 form selected is merely illustrative but does not

exhaust the possible physical embodiments of the idea of means underlying the invention.

What I claim as new and desire to secure by Letters Patent of the United States, is:

1. In a wire connector binding post of the type 80 including a central threaded bolt, the combination of a metallic sleeve fitting about the bolt, an annulus, formed with a wire receiving aperture, surrounding the sleeve and connected thereto by a bottom wall, an apertured disc fitting around the rod and extending within the annulus with its upper face projecting beyond the annulus, and a nut threaded on the bolt and engaging said upper face of the disc for forcing it downwardly against the wire extending through 85 said aperture and resting on said bottom wall.

2. In a wire connector binding post, the combination of a threaded bolt, a wire-receiving member adapted to slide over the bolt and provided with an annular groove having parallel inner and outer walls, said outer wall being laterally slotted to receive a wire, an annular disc slidable over said bolt and having a thickness sufficient to extend between said parallel walls with its inner face bearing upon a wire within the 100 groove and its outer face beyond said walls, and a nut threaded on said bolt and adapted to bear upon said outer face to force said lower face against the wire.
